Patented Nov. 4, 1924.

UNITED STATES PATENT OFFICE.

WILLIAM E. SMITH, OF LOS ANGELES, CALIFORNIA.

AUXILIARY APPARATUS FOR COOLING SYSTEMS.

Application filed January 12, 1922. Serial No. 528,659.

To all whom it may concern:

Be it known that I, WILLIAM R. SMITH, a citizen of the United States, residing at Los Angeles, in the county of Los Angeles and State of California, have invented new and useful Improvements in Auxiliary Apparatus for Cooling Systems, of which the following is a specification.

My invention relates to cooling systems for automobile internal combustion engines, and the purpose of my invention is the provision of an apparatus adapted for association with any cooling system of standard construction which operates to collect all water and steam ordinarily expelled from the radiator and to cool the water so collected and return the same to the cooling system whereby, the cooling efficiency of the steam is greatly increased and without the loss of water.

It is also a purpose of my invention to provide a cooling apparatus which can be employed to effect an injection of water from an exterior source into the system and in such manner as to eliminate the necessity of removing the radiator cap.

I will describe one form of apparatus embodying my invention and will then point out the novel features thereof in claims.

30 In the accompanying drawings,

Figure 1 is a view showing in side elevation a cooling system for automobile engines having applied thereto one form of apparatus embodying my invention.

35 Figure 2 is an enlarged detail sectional view showing the condensing tank comprised in the apparatus shown in Figure 1.

Figure 3 is a top plan view of the tank shown in Figure 2.

40 Figure 4 is a fragmentary sectional view of the tank shown in Figure 2.

Figure 5 is a detail view partly in section showing one form of water level indicator embodying my invention and comprised in the apparatus shown in Figure 1.

Similar reference characters refer to similar parts in each of the several views.

Referring specifically to the drawings and particularly to Figure 1, my invention in its present embodiment comprises a water collecting and steam condensing tank designated generally at T, and which is adapted to be supported at the forward end of an internal combustion engine shown diagrammatically and indicated at E in Figure 1, by means of a bracket B so as to rigidly sup-

port the tank between a radiator R and the engine E. The upper end of the tank T is provided with a cover 15 formed with a suitable opening to receive a short section of pipe 16 connected to a union 17, with the latter in turn in communication with a flexible pipe 18. The upper end of the latter is connected to the radiator R at a point adjacent its upper end as indicated at 19 so that excess water and steam from the radiator can pass downwardly through the pipes 18 and 16 into the tank T. The water and steam entering the tank T pass into a tubular member 20 having its lower end open and provided with perforations 21 adjacent the lower end and through which water passes into the tank at a point adjacent the bottom thereof. The lower end of the tank T is adapted to communicate with a pipe P constituting a part of the usual cooling system for an internal combustion engine, through a pipe 22 connected at its upper end to a T 23, with the latter in turn connected to a short section of pipe 24 which communicates with the lower end of the tank T. The T 23 carries a petcock 25 by means of which the tank can be drained from time to time to effect removal of sediment and other foreign matter. The lower end of the pipe 22 is connected to the pipe P as clearly shown in Figure 1, and in the vertical portion of the pipe 22 a valve 26 is provided having an operating arm 27 connected thereto for effecting a closing or opening of the valve to connect or disconnect the tank T from the pipe P. To effect a manual operation of the valve 26, a flexible cable 28 is connected at one end to the free end of the arm 27, and at its opposite end to a handle or button 29 disposed on the instrument board of an automobile and in convenient position to allow the manual operation thereof in effecting actuation of the arm 27. The spring 30 is connected to the free end of the arm 27 and to a split ring 31 embracing the pipe P, this spring serving to normally urge the arm 27 to a position in which the valve 26 is closed. The operation of the cable 28 will therefore be in opposition to the spring 30 so that when the valve 26 is moved to open position by pulling on the button 29, the spring 30 will operate to close the valve when the button is released.

As in the usual cooling system for internal combustion engines, the pipe P serves to connect the radiator R with a pump M,

the latter serving to constantly circulate the water through the cooling system. In conjunction with the usual cooling system a fan F is employed directly behind the radiator R, and by consideration of Figure 1 it will be clear that the arrangement of the tank T is such that it is disposed rearwardly of the fan F so as to be within the draft of air created by the fan rearwardly through the 10 radiator.

Referring to Figure 2, the tank T contains an indicator for indicating the amount of water contained within the tank. This indicator in the present instance comprises 15 a rod 32 to the lower end of which is secured a float 33, while its upper end is provided with a plug 34 threadedly fitted within a collar 35 secured to the top 15. The upper end of the rod 32 extends through a 20 suitable opening formed within the cover 15 so that when the plug 34 is disengaged from the collar 35, the float 33 will be free to move the rod vertically so as to indicate the exact level of water within the tank.

25 To allow of an overflow from the tank T should it become completely filled with water, an overflow pipe 36 is provided which, as shown in Figure 2, is extended vertically within the tank with its lower 30 end secured within the bottom of the tank as shown. Its upper end carries a cap 37 of tubular form and which is secured to the pipe so as to provide a passage-way 38 through which the water passes in entering 35 the upper end of the pipe. The upper end of the cap 37 is perforated as shown to prevent the forming of a siphon in the pipe and cap. For the purpose of preventing 40 splashing and undue movement of the water within the tank a float 39 is arranged within the tank in the manner shown in Figure 2, with the float formed with suitable openings to allow of its unrestricted 45 movement with respect to the cap 37 and the rod 32.

As shown in Figure 4, the cover 15 is provided with a filling cap 40 through which the tank can be filled with water, as it is desirable in practice to partially fill the tank 50 and to thus carry an auxiliary supply of water. As shown in Figures 2 and 3, the cover 15 is also provided with a vent opening 41 which allows of the proper circulation of air into and out of the tank, as will 55 be understood.

In Figures 1 and 5 I have shown one form 60 of water level indicator adapted for use in conjunction with the apparatus shown in Figure 1. This indicator comprises a casing 42 sustained on a radiator cap 43 and provided with a central opening 44 which is in communication with a tubular member 45. The member 45 is adapted to extend 65 into the radiator when the cap 43 is in applied position and to thus allow the passage

of water upwardly into the opening 44 where it enters a transparent tube 45 for lifting a ball 46 to indicate the level of water within the radiator. The upper end of the tube 45 is provided with an opening 70 45^a, and the upper end of the casing 42 is likewise provided with an opening 47. These openings 45^a and 47 allow of the passage of air into and out of the tube 45 to effect the proper operation of the ball 46 under the 75 action of the water. Although I have specifically described a particular form of water level indicator, it is to be understood that any form of indicator can be employed in conjunction with the apparatus shown in 80 Figure 1.

The operation of the apparatus is as follows: As previously stated, the tank T is partially filled with water through the filling cap 40. With the tank T connected to the radiator R and the pipe P in the manner shown, it will be clear that any overflow 85 of water from the radiator R or any steam as the result of excessive heating of water in the cooling system, will all pass from the radiator through the pipe 18 and to the tank T, the tubular member 20 serving to admit this excess water and steam into the tank at the bottom thereof and within the water already contained within the tank. As the tank is disposed directly in the rear 90 of the fan wheel F it will be manifest that the water contained within the tank is subjected to the cooling action of the fan wheel, and that the steam in the tank is also condensed. By observing the indicator, the operator of an automobile can determine the amount of water contained in the cooling 95 system, and should this be below a prescribed level, the water in the tank T can 100 be supplied to the cooling system by an opening of the valve 26, thus restoring the normal supply of water contained in the 105 cooling system.

From the foregoing operation, it will be 110 manifest that the apparatus operates to conserve the water originally supplied to the cooling system and to collect and cool water and steam expelled from the radiator. This 115 obviously eliminates the necessity of stopping to fill the radiator with water from time to time and the disadvantages attendant thereto.

In Figure 1 I have shown a vertical portion of the pipe 22 provided with a manually operated valve 48 and a flexible pipe or hose 49 connected to the pipe between the valves 26 and 48. The pipe 49 is adapted to extend to a remote point for connection with a source 125 of water supply such as the usual auxiliary water tank carried upon the running board of an automobile. The pipe 49 is also provided with a valve 50. In operation, the valve 48 is closed and the valve 50 opened, and when the valve 26 is moved to open position 130

tion and with the pump M in operation, the suction created in the pipe 22 by the circulation of water in the cooling system can be utilized to create a suction within the pipe 49 35 and thereby draw the water from the source of supply into the cooling system. This eliminates the trouble of filling the tank T from time to time through the filling cap 40.

Although I have herein shown and described only one form of auxiliary cooling apparatus embodying my invention it is to be understood that various changes and modifications may be made herein without departing from the spirit of the invention 15 and the spirit and scope of the appended claims.

What I claim is:

1. In combination, a cooling system for internal combustion engines including a radiator, a pump, and a pipe connecting the pump with the radiator, a pipe extension formed on said pipe including a flexible section adapted to extend to a remote source of water supply, and a valve in the pipe extension so that additional water may be drawn into the system by attaching the flexible pipe section to a source of water supply and opening the valve.

2. In combination, a cooling system for internal combustion engines including a radiator, a fan wheel, a pump and a pipe connecting the pump with the bottom of the radiator, an auxiliary cooling apparatus comprising a tank arranged in the rear of the

radiator and fan wheel and connected with the top of the radiator, valve controlled means for connecting the tank at its bottom to said pipe, and a pipe connected to said means for the purpose described.

3. In combination, a cooling system for internal combustion engines including a radiator, a fan wheel, a pump and a pipe connecting the pump with the bottom of the radiator, an auxiliary cooling apparatus comprising a tank arranged in the rear of the radiator and fan wheel and connected with the top of the radiator, valve controlled means for connecting the tank at its bottom to said pipe, a filling pipe connected to said means at a point below the valve of said means, and a second valve between said first valve and connecting pipe.

4. An auxiliary cooling system combined with a radiator and a return pipe and comprising a tank, means for connecting the tank to the head of a radiator, a pipe in communication with the bottom of the tank and adapted for connection to the return pipe of a radiator, a second pipe adapted for connection with a source of water supply and connected to the first pipe, a valve in the second pipe, and two valves in the first pipe at opposite sides of the connection with the second pipe.

In testimony whereof I have signed my name to this specification.

WILLIAM R. SMITH.
